UNITED STATES PATENT OFFICE.

AMBROSE RIDD, OF NEWPORT, KENTUCKY.

APPARATUS FOR BLUING METAL SHEETS.

No. 823,226.

Specification of Letters Patent.

Patented June 12, 1906.

Application filed September 6, 1905. Serial No. 277,242.

To all whom it may concern:

Be it known that I, AMBROSE RIDD, a citizen of the United States, residing at Newport, in the county of Campbell and State of Kentucky, have invented a new and useful Apparatus for Bluing Metal Sheets, of which the following is a specification.

This invention relates to the manufacture of sheet iron and steel, and more especially to that class of sheet-steel having a highly-finished surface and known as "Russian sheet-iron."

In the manufacture of sheet metal of this class it is desirable for commercial purposes to produce a sheet of bluish color; but this cannot always be accomplished, especially where the metal is handled at comparatively high temperatures. In the annealing-ovens the temperature often reaches 1,000° Fahrenheit or more, and the sheets when cooled and withdrawn from the oven are sometimes of a color other than blue, generally a light yellow or straw.

In the methods now generally practiced these off-color sheets are passed through highly-heated rolls for the purpose of restoring the bluish tinge; but this additional passage through the rolls after the sheet has been finally planished and annealed will in many cases destroy the enamel-like surface of the sheet and materially reduce its value.

It is the object of the present invention to restore to the sheets the bluish tinge without danger of cracking or otherwise injuring the same, and this is accomplished by subjecting the sheets to a temperature sufficiently high for the purpose without again rolling or otherwise mechanically treating said sheets.

A further object of the invention is to provide an improved apparatus in the nature of an oven wherein the opposite sides of the sheets may be subjected to practically the same temperature, so that through uniform heating there will be no danger of warping or buckling of the sheet and both of its surfaces will present approximately the same appearance.

A still further object of the invention is to provide a novel form of tempering-oven through which the sheet of metal may be traversed and subjected to the proper temperature for changing the film of oxid to the desired color.

A still further object of the invention is to provide a novel form of tempering-oven wherein a current of heated fluid, such as air, may be caused to circulate around the oven or may directly enter the oven as required.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of an apparatus constructed in accordance with the invention and designed to carry the improved method of heating sheets into effect. Fig. 2 is a longitudinal sectional elevation of the same. Fig. 3 is a transverse sectional view of the same on the line 3 3 of Fig. 2.

Similar numerals of reference are employed to indicate corresponding parts throughout the several figures of the drawings.

The apparatus comprises an outer casing 10, at the center of which is an oven 11, that is open at both ends, and the end portions of the casing between the mouth of the oven and the vertical and horizontal walls of said casing are closed. At the central portion of the bottom of the casing is an inlet 12, through which a heated fluid is directed into the casing, the fluid encircling the vertical and horizontal walls of the opening and heating the latter to the desired temperature.

Arranged within the oven is a series of rollers 13, the plane of the tops of the rollers being preferably at a point midway of the height of the oven, so that a sheet of metal supported on said rollers will have its upper and lower surfaces subjected to approximately the same temperature. The spindles of these rollers extend out through the side of the casing, and on each spindle is secured a sprocket-wheel 16, and all of said sprocket-wheels are connected by a link belt 17, by which movement is transmitted to all of said rollers for the purpose of traversing the sheet from end to end of the oven, the rollers being turned

at slow speed and a single passage of the sheets through the oven being sufficient to accomplish the desired result.

The hottest portion of the oven is of course directly above the inlet 12, and in order that the color of the sheet may be inspected transparent panels 18 are arranged on the top of the oven and in the top of the casing, said panels being in alinement with each other and permitting the operator to ascertain the condition of the sheets. A thermometer 20 is also provided in order that the temperature of the apparatus may be ascertained.

In some cases it is desirable to permit the heated fluid to make direct contact with the sheet being treated, and for this purpose the top and bottom walls of the oven are formed of pivotally-mounted shutters or dampers 22, the pivot-pintles of which are extended to the exterior of the casing and are provided with rocker-arms 23, said rocker-arms being connected to bars 24 and said bars being connected together by an operating-handle 25, so that all of the shutters or dampers may be simultaneously opened and closed.

In practice, the sheets to be treated are introduced at one end of the oven, and the latter being heated to the proper temperature the rollers are gradually turned and the sheets are gradually fed toward the opposite end of the oven, passing under the transparent panel, so that the operator may view the result, and, if necessary, increase or decrease the temperature, or he may open or close the oven-shutters to a greater or less extent in accordance with the character of the sheet being treated. The temperature may be varied to some extent, but will range from 530° for a light purple to 610° for a pale blue.

In the construction of the apparatus doors or dampers 26 are preferably placed at the opposite ends of the main chamber for the purpose of allowing the escape of the heated fluid, and such doors or dampers are shown in Fig. 1 as connected to the operating-bars 24 by means of links 27, the arrangement being such that when the shutters or dampers 22 are closed the dampers 26 will be opened, and when the dampers 26 are closed the dampers 22 are open. The heated fluid, especially where air is used, may be conducted back to the heating appliance and again directed through the supply-tube 12.

Metal sheets treated in the manner described retain the enamel-like surface produced by condensation of the film of oxid and will not crack or otherwise injure the finish of the sheet, while uniformity of color of the entire product of the mill is insured at a comparatively small cost.

Having thus described the invention, what is claimed is—

1. In apparatus of the class described, an

oven open at its opposite ends, sheet-supporting means arranged within the oven, a 65 casing surrounding the bottom, top and side walls of the oven, the lower central portion of the casing having means for directing a heating fluid against the lower central portion of the oven, and the opposite ends of the 70 casing having outlets for the heating fluid, whereby a high temperature may be maintained at the central portion of the oven and gradually reduce toward both ends thereof.

2. In apparatus of the class described, an 75 oven open at its opposite ends to permit the continuous passage of sheets to be annealed, sheet-supporting means arranged within and above the floor of the oven, a casing surrounding the bottom, top and side walls of 80 the oven, there being an inlet for a heating fluid at the lower central portion of the casing, and outlets for such fluid at the upper outer ends of the casing.

3. In apparatus of the class described, a 85 casing, an oven arranged within and having its top, bottom and side walls surrounded by and spaced from said casing, the opposite ends of the oven being open to permit the continuous passage of sheets to be annealed, 90 shutters or dampers arranged in the walls of the oven for controlling the passage of a heating fluid into said oven.

4. In apparatus of the class described, an outer casing or jacket, an oven arranged 95 within the same, shutters or dampers arranged in the top and bottom walls of the oven, and means for opening and closing said shutters.

5. In apparatus of the class described, a 100 casing or jacket, an oven arranged within the same, a plurality of shutters or dampers arranged in the top and bottom walls of said oven, and shutter-operating members extending to the exterior of the casing and connected for mutual movement.

6. In apparatus of the class described, an outer casing or jacket, an oven arranged within the same, a plurality of shutters or dampers arranged in the top and bottom 110 walls of the oven, the pintles of said dampers extending outward through said casing, rocker-arms connected to said pintles, and means for connecting all of such rocker-arms for mutual movement.

7. In apparatus of the class described, an outer casing or jacket having an escape-opening, a damper for closing the same, an oven arranged within said casing, and a plurality of dampers or shutters in the top and bottom 120 walls of said oven.

8. In apparatus of the class described, an outer casing having entrance and escape openings, dampers closing the escape-openings, an oven arranged within the casing and also having openings or shutters, and a sim- 125

gle actuating means connecting all of the dampers or shutters, said actuating means being so arranged that when the dampers of the oven are moved to closed position the 5 dampers of the casing will be moved to open position.

In testimony that I claim the foregoing as

my own I have hereto affixed my signature in the presence of two witnesses.

AMBROSE RIDD.
